CLOCK

Ellsworth R. Danz, La Salle, Ill., assignor to General Time Corporation, New York, N. Y., a corporation of Delaware

Application September 8, 1949, Serial No. 4,913

Term of patent 14 years

(Cl. D42—7)

To all whom it may concern:

Be it known that I, Ellsworth R. Danz, a citizen of the United States, residing at La Salle, in the county of La Salle and State of Illinois, have invented a new, original, and ornamental Design for a Clock, of which the following is a specification, reference being had to the accompanying drawing, forming a part thereof.

Figure 1 is a perspective view of a clock embodying my new design.

Figure 2 is a front elevational view of said clock.

Figure 3 is a side elevational view of said clock.

Figure 4 is a front elevational view of the base removed from said clock.

The essential features of my design present a clock having a face which is very large in respect to the over-all dimensions of the clock. The face is covered by a curved crystal which extends

to a wide, massive band that encircles the largest dimension of the clock. These features are in combination with the base having an open configuration, as illustrated in the drawing.

I claim:

The ornamental design for a clock, substantially as shown and described.

ELLWORTH R. DANZ.
